[57] CLAIM

The ornamental design for a perfume bottle, as shown, and described.

DESCRIPTION

FIG. 1 is a perspective view of a perfume bottle showing
my new design;

FIG. 2 is a top plan view;

FIG. 3 is an elevational view;

FIG. 4 is an elevational view of the bottle rotated approximately 108° from the position of FIG. 3; and

FIG. 5 is a perspective view showing a modified form of my new design.
